DETERMINATION OF SODIUM HYDROXIDE
IN PRESENCE OF THE ALUMINATEPerle N. Burkard, Wyandotte, Mich., assignor, by
mesne assignments, to Wyandotte Chemicals
CorporationNo Drawing. Application January 6, 1941,
Serial No. 373,323

8 Claims. (Cl. 23—230)

The present invention relates to an analytical method for determining both the caustic alkali and aluminate content of alkaline detergent solutions.

It also provides a process for regenerating the alkalinity or increasing the hydroxyl ion concentration in caustic alkali solutions which, due to their conditions and circumstances of usage, have become contaminated with an alkali aluminate. My invention is equally well applicable to caustic alkali solutions in which the caustic alkali is sodium or potassium hydroxide and the corresponding contaminating compound is sodium or potassium aluminate. Sodium hydroxide, however, is the caustic alkali most commonly used commercially in detergent, cleaning and washing solutions. As such solutions come in contact with metallic aluminum, a chemical reaction takes place whereby some or all of the alkali is converted into sodium (or potassium) aluminate, thereby decreasing the alkaline intensity of the solution and its corresponding detergent and germicidal ability.

My invention is based upon the discovery that the addition of sodium fluoride to such solutions which have become contaminated with sodium or potassium aluminate, results in a substantial increase in the alkalinity thereof; in fact, in tripling the alkalinity or hydroxyl ion concentration of the aluminate. This discovery is primarily of a two-fold utility.

First it provides a new convenient and reliable analytical method for determining both the caustic alkali and aluminate content of alkaline solutions which have become contaminated with alkali metal aluminate; and secondly, as already indicated it provides a convenient method of regenerating the alkalinity of such solutions of deficient alkaline capacity.

In the art of alkaline cleaning for the food and beverage industries, food containers, beer bottles, milk bottles, and numerous other articles are washed in alkaline solutions containing sodium or potassium hydroxide in combination with alkali metal salts, such as trisodium phosphate, tetrasodium pyrophosphate, sodium hexameta phosphate, borax, sodium carbonate, silicates and other detergent ingredients, such as synthetic wetting agents, and anti-foaming agents, to remove dirt, grease, and other foreign contaminants. Particularly in the case of bottle washing, sterile bottles, as well as clean bottles, must result from this cleaning process.

Sodium hydroxide is one of the most effective and therefore is most widely used as a major

ingredient in bottle washing compounds. Various other alkalies, such as the alkali metal phosphates, carbonates, bicarbonates, borates and silicates, are used in sodium hydroxide to improve its rinsing properties and to condition the water for more effective cleaning.

Such alkali detergent solutions, when coming in contact with metallic aluminum, such as that found in metal foil labels, bottle caps, utensils and the like, reacts to form alkali metal aluminate according to the following equation:

15 The other alkali metal salts present also react with the aluminum in a similar manner, forming additional aluminate. The presence of the aluminate in such solutions is undesirable, first, because it is a weaker and much less effective alkali, thus depreciating the alkaline capacity or hydroxyl ion concentration of the solution as a whole; and secondly, because it is impossible, with analytical testing methods heretofore known, reliably to determine the actual amount of alkali metal hydroxide present in the solution.

20 It is, therefore, the general object and nature of my invention to provide a method for regenerating the alkalinity of alkaline, detergent solutions which have become contaminated with alkali metal aluminate, as well as to provide a convenient and reliable analytical testing method for determining the amount of alkali metal hydroxide or caustic alkali in the solution, even in the presence of the aluminate.

25 A further object and advantage of the invention is to make indicator color changes more readily visible by providing an internal, white background in the solution, so that the chemical reaction end points occurring in the performance of my analytical method may be accurately determined in dirty and soil-contaminated solutions.

30 To the accomplishment of the foregoing and related ends, said invention, then consists of the steps hereinafter fully described and particularly pointed out in the claims.

35 The following description sets forth in detail one approved method of carrying out the invention, such disclosed method, however, constituting but one of the various ways in which the principle of the invention may be used. Although, as above indicated, the invention is equivalently applicable to alkali metal compound solutions in which the hydroxides and contaminating aluminates are those of sodium or potassium, the following detailed description will suit-

ably, and for the sake of convenience, be confined to the sodium compounds.

As previously pointed out, the contamination of alkali, detergent solutions with sodium aluminate has presented a serious problem in the art. The seriousness of this problem can be appreciated by considering that the aluminum labels from 210,000 average 12-ounce beer bottles will completely convert all the sodium hydroxide in 600 gallons of a 3 percent sodium hydroxide solution into sodium aluminate, a milder and much less effective alkali. In addition, by the methods commonly used for titrating alkaline solutions, this solution will still show a 3 percent sodium hydroxide content when no sodium hydroxide is present.

For operating efficiency and to comply with certain public health regulations, it is desirable to maintain a definite sodium hydroxide content in the solution. Some State laws, for instance, require a 3 percent sodium hydroxide content. To do this, a reliable method of testing the solution must be employed. The methods used in the past have been:

(1) By determining the specific gravity of the solutions with a hydrometer and reading the sodium hydroxide content from a conversion table.

(2) By the double titration method employing a standard acid solution, phenolphthalein indicator, and methyl orange indicator and calculating the sodium hydroxide content.

(3) By precipitating the other alkaline salts with neutral barium chloride and titrating the sodium hydroxide which remains in solution with a standard acid using phenolphthalein indicator solution.

Method (1) is accurate for sodium hydroxide solutions, and, since sodium hydroxide is seldom used alone, this method is not accurate enough for accepted use.

Method (2) is accurate only for solutions containing sodium hydroxide in combination with sodium carbonate and/or trisodium phosphate.

Method (3) has been most widely used and for general use is the most accurate, but it still is not sufficiently accurate for solutions contaminated with sodium aluminate.

I have discovered that the alkalinity of a sodium aluminate solution above a pH of 8.2 can be tripled by adding an excess of sodium fluoride, preferably in the form of a powder. The chemical reaction that takes place cannot at this time be fully explained. Sodium aluminate, NaAlO_2 , reacts in the presence of sodium fluoride as if its formula were Na_2AlO_4 . Thus, by adding a chemical equivalent amount of powdered sodium fluoride to a solution containing sodium aluminate, the spent alkalinity due to the presence of the sodium aluminate is regenerated. Such a chemical equivalent amount of the sodium fluoride is, of course, estimated upon the basis of the probable amount of sodium aluminate present and is added in excess thereof in order to insure a safe margin of complete reaction and complete alkaline regeneration.

The mechanism of this reaction can be employed in determining the sodium hydroxide content of alkaline solutions containing sodium aluminate by a rapid titration method. In the performance of this analytical method, excess barium chloride is added to a solution containing sodium hydroxide, which is contaminated with sodium aluminate and which solution also contains one or more of the alkali metal salts of weak acids such as sodium carbonate, trisodium phosphate,

tetrasodium pyrophosphate, sodium hexameta-phosphate, borax, sodium bi-carbonate, sodium silicate and sub-silicates. The solution is then titrated with an acid solution of known strength

5 using a few drops of 0.5 percent alcoholic phenolphthalein solution as the indicator. When the end point is reached at a pH of approximately 8.2, only the alkalinites of the sodium hydroxide and the sodium aluminate have been neutralized.

10 The other alkaline materials have reacted with the barium chloride precipitating barium salts and forming neutral sodium chloride. If at this point an excess, usually about 0.5 to 1.0 gram for every 10 ml. of alkaline solution, of sodium fluoride powder be added, the solution will again turn pink due to the alkalinity formed by the reaction of the aluminate and the sodium fluoride. I have discovered that this increase in alkalinity upon the addition of the sodium fluoride powder is equal to twice the alkalinity of the sodium aluminate present in the original solution.

Applying the above-stated facts to chemical analysis, I have discovered that, by titrating an aliquot portion of an alkaline solution with an acid of known strength in the presence of barium

25 chloride and phenolphthalein indicator solution, the number of milliliters of acid used in this titration minus $\frac{1}{2}$ the number of milliliters of acid required to reach the second end point after the addition of sodium fluoride powder is equal to the number of milliliters of acid required to neutralize the sodium hydroxide present in the aliquot portion of the alkaline solution. If 1.000 normal acid were used, each milliliter of acid is equivalent to 0.040 gram of sodium hydroxide.

30 For example, in titrating 10 milliliters of an alkaline solution having a specific gravity of 1.03 to which barium chloride has been added in excess of that amount required to precipitate car-

40 bonates, phosphates, etc., with 1.000 normal sulfuric acid using 0.5% alcoholic phenolphthalein as the indicator solution; 16.5 milliliters of the acid were required to reach the end point. After the addition of sodium fluoride, 10.4 milliliters of

45 additional acid was required to reach the second end point. Then:

$$\% \text{NaOH} = \frac{(16.5 - 10.4/2) \times .040 \times 100}{10 \times 1.03} = 4.4$$

50 In practical field testing, I employ 2.56 normal sulfuric acid and titrate 10-milliliter portions of the cleaning solution. The use of 2.56 normal acid in place of 2.50 normal acid compensates approximately for the density of the average bottle washing solution in calculation of percentage of sodium hydroxide or sodium aluminate content. By doing this, each milliliter of acid used becomes equivalent to 1 percent sodium hydroxide. According to this procedure, the titration values in the preceding paragraph then become:

55 1st end point ..... 6.44 milliliters of 2.56 N acid
2nd end point after the addition of sodium fluoride ..... 4.07 milliliters of 2.56 N acid

60 Then: $\% \text{NaOH} = 6.44 - 4.07/2 = 4.4$

65 The sodium aluminate can be obtained by multiplying the milliliters of acid used in the second titration by a constant factor. This factor is derived as follows:

70 Since all of the acid used in the second titration is used in titrating the alkali liberated by the reaction of sodium aluminate and sodium fluoride, it means that 1 molecule of sulphuric acid is re-

quired in the second titration for every molecule of sodium aluminate present in the original solution. Thus, on the basis of molecular weights, 81.97 grams of sodium aluminate is equivalent to 98.06 grams of sulphuric acid. Each ml. of 2.56 N sulphuric acid contains .1255 grams of sulphuric acid, and therefore, each ml. of 2.56 N sulphuric acid used in the second titration is equivalent to .1049 grams of sodium aluminate according to the following equation:

$$\frac{81.97}{98.06} \times .1255 = 0.1049 \text{ grams NaAlO}_2$$

The above factor is converted into terms of percent of sodium aluminate by multiplying it by 100 and dividing by 10.3, viz.

$$\frac{.1049 \times 100}{10.3} = 1.019$$

The percent of sodium aluminate in our illustrative example is thus calculated as follows:

$$\begin{aligned} \% \text{ NaAlO}_2 &= 1.019 \times 4.07 \\ &= 4.15 \end{aligned}$$

In some instances, it might be found necessary to adjust the above derived factor of 1.019 to compensate for the presence of other chemicals in solution and in practical field tests. This adjustment can be made in the factor by titrating a number of solutions of known strength and calculating the factor.

The method herein described works equally well for solutions from their freezing to their boiling points and for dirty solutions, as well as clean solutions. To overcome the necessity of filtering dirty solutions, I have purposely used barium chloride and sulfuric acid to form an internal, white background of white barium sulfate to make indicator color changes easily visible.

It will be apparent to those skilled in the art that equivalent indicators other than the phenolphthalein indicator hereinabove mentioned may be employed to indicate the proper end point during the neutralizing or titrating steps of my analytical method.

By the same token, equivalent neutralizing acids, made up in standard solutions, may likewise be employed in lieu of the standard sulfuric acid solutions hereinabove described.

The above-described method for determining the caustic alkali and sodium aluminate content of solutions is highly accurate and reliable for practically all alkaline detergents encountered in the field, even those containing silicates in the amount of up to 1% sodium silicate. Above that amount, silicates will have some effect upon the accuracy of the sodium hydroxide content determinations, but any such higher percentage of sodium silicate is rarely encountered in solutions contaminated with aluminum, for the simple reason that detergents containing silicates are not ordinarily employed if the solution is likely to be placed in contact with aluminum.

Other modes of applying the principle of my invention may be employed instead of the one explained, change being made as regards the method herein disclosed, provided the step or steps stated by any of the following claims or the equivalent of such stated step or steps be employed.

I, therefore, particularly point out and distinctly claim as my invention:

1. The method of determining the amount of alkali metal hydroxides in solutions thereof contaminated with alkali metal aluminate, consisting in the steps of neutralizing the alkalinity

of said hydroxides and said aluminate, adding sodium fluoride thereto in an amount sufficient to react completely with the aluminate, thereby regenerating the alkalinity of said aluminate to twice its original amount, and then neutralizing the resultant solution.

2. The method of determining the amount of sodium hydroxide in solutions thereof contaminated with sodium aluminate, consisting in the steps of neutralizing the alkalinity of said hydroxide and said aluminate, adding sodium fluoride thereto in an amount sufficient to react completely with the sodium aluminate, thereby regenerating the alkalinity of said aluminate to twice its original amount, neutralizing the resultant solution, and measuring the sodium hydroxide chemical equivalent amount of neutralizing reagent required in each of the aforesaid neutralizing steps.

3. The method of determining the amount of sodium hydroxide and sodium aluminate present in the same solution, consisting in the steps of neutralizing the alkalinity of said hydroxide and said aluminate, adding sodium fluoride thereto in an amount sufficient to react completely with the sodium aluminate, thereby regenerating the alkalinity of said aluminate to twice its original amount, neutralizing the resultant solution, and measuring the sodium hydroxide chemical equivalent amount of neutralizing reagent required in each of the aforesaid neutralizing steps.

4. The method of determining the amount of sodium hydroxide in a solution containing alkali metal salts of weak acids in addition thereto, and contaminated with sodium aluminate, consisting in the steps of precipitating said alkali metal salts, whereby the sodium hydroxide and sodium aluminate remain in solution, neutralizing the alkalinity of said hydroxide and said aluminate, adding sodium fluoride thereto in an amount sufficient to react completely with the sodium aluminate, thereby regenerating the alkalinity of said aluminate to twice its original amount, and then neutralizing the resultant solution.

5. The method of determining the amount of sodium hydroxide in a solution containing alkali metal salts of weak acids in addition thereto and contaminated with sodium aluminate, consisting in the steps of precipitating said alkali metal salts, whereby the sodium hydroxide and sodium aluminate remain in solution, neutralizing the alkalinity of said hydroxide and said aluminate, adding sodium fluoride thereto in an amount sufficient to react completely with the sodium aluminate, thereby regenerating the alkalinity of said aluminate to twice its original amount, then neutralizing the resultant solution, and measuring the sodium hydroxide chemical equivalent amount of neutralizing reagent required in each of the aforesaid neutralizing steps.

6. The method of determining the amount of sodium hydroxide and sodium aluminate, both present in the same solution, and in which alkali metal salts of weak acids are also present, consisting in the steps of precipitating said alkali metal salts whereby the sodium hydroxide and sodium aluminate remain in solution, neutralizing the alkalinity of the sodium hydroxide and sodium aluminate, adding sodium fluoride thereto in an amount sufficient to react completely with the sodium aluminate, thereby regenerating the alkalinity of said aluminate to twice its original amount, neutralizing the resultant solution, and measuring the sodium hydroxide chemical equivalent amount of neutralizing reagent required in each of the aforesaid neutralizing steps.

7. The method of determining the amount of sodium hydroxide and sodium aluminate, both present in the same solution, and in which alkali metal salts of weak acids are also present, consisting in the steps of precipitating said alkali metal salts whereby the sodium hydroxide and sodium aluminate remain in solution, neutralizing the alkalinity of the sodium hydroxide and sodium aluminate, adding sodium fluoride thereto in an amount sufficient to react completely with the sodium aluminate, thereby regenerating the alkalinity of said aluminate to twice its original amount, neutralizing the resultant solution,

8. The method of determining the amount of sodium hydroxide in a solution containing alkali metal salts of weak acids in addition thereto and contaminated with sodium aluminate, consisting in the steps of precipitating said alkali metal salts, whereby the sodium hydroxide and sodium aluminate remain in solution, neutralizing the alkalinity of said hydroxide and said aluminate, adding sodium fluoride thereto in an amount sufficient to react completely with the sodium aluminate, thereby regenerating the alkalinity of said aluminate to twice its original amount, then neutralizing the resultant solution, and measuring the sodium hydroxide chemical equivalent amount of neutralizing reagent required in each of the aforesaid neutralizing steps.

9. The method of determining the amount of sodium hydroxide and sodium aluminate, both present in the same solution, and in which alkali metal salts of weak acids are also present, consisting in the steps of precipitating said alkali metal salts whereby the sodium hydroxide and sodium aluminate remain in solution, neutralizing the alkalinity of the sodium hydroxide and sodium aluminate, adding sodium fluoride thereto in an amount sufficient to react completely with the sodium aluminate, thereby regenerating the alkalinity of said aluminate to twice its original amount, neutralizing the resultant solution,

10. The method of determining the amount of sodium hydroxide and sodium aluminate, both present in the same solution, and in which alkali metal salts of weak acids are also present, consisting in the steps of precipitating said alkali metal salts whereby the sodium hydroxide and sodium aluminate remain in solution, neutralizing the alkalinity of the sodium hydroxide and sodium aluminate, adding sodium fluoride thereto in an amount sufficient to react completely with the sodium aluminate, thereby regenerating the alkalinity of said aluminate to twice its original amount, neutralizing the resultant solution,

11. The method of determining the amount of sodium hydroxide and sodium aluminate, both present in the same solution, and in which alkali metal salts of weak acids are also present, consisting in the steps of precipitating said alkali metal salts whereby the sodium hydroxide and sodium aluminate remain in solution, neutralizing the alkalinity of the sodium hydroxide and sodium aluminate, adding sodium fluoride thereto in an amount sufficient to react completely with the sodium aluminate, thereby regenerating the alkalinity of said aluminate to twice its original amount, neutralizing the resultant solution,

12. The method of determining the amount of sodium hydroxide and sodium aluminate, both present in the same solution, and in which alkali metal salts of weak acids are also present, consisting in the steps of precipitating said alkali metal salts whereby the sodium hydroxide and sodium aluminate remain in solution, neutralizing the alkalinity of the sodium hydroxide and sodium aluminate, adding sodium fluoride thereto in an amount sufficient to react completely with the sodium aluminate, thereby regenerating the alkalinity of said aluminate to twice its original amount, neutralizing the resultant solution,

and measuring the sodium hydroxide chemical equivalent amount of neutralizing agent required in each of the aforesaid neutralizing steps.

7. The method of determining the amount of sodium hydroxide in a solution containing alkali metal salts of weak acids in addition thereto and contaminated with sodium aluminate, consisting in the steps of adding barium chloride to said solution in excess of the amount required to precipitate said alkali metal salts, thereby leaving the sodium hydroxide and sodium aluminate in solution, adding an indicator to said solution and titrating to the neutral end point with a standard solution of sulfuric acid, thereby forming a white background of barium sulphate in the solution, adding sodium fluoride to the solution in an amount sufficient to react completely with the sodium aluminate, thereby regenerating the alkalinity of said aluminate to twice its original amount, and again, titrating to the neutral end point with a standard solution of sulfuric acid.

8. The method of determining the amount of sodium hydroxide in a solution containing alkali metal salts of weak acids in addition thereto and contaminated with sodium aluminate, consisting in the steps of adding barium chloride to said solution in excess of the amount required to precipitate said alkali metal salts, thereby leaving the sodium hydroxide and sodium aluminate in solution, adding an indicator to said solution and titrating to the neutral end point with a 2.56 normal solution of sulfuric acid, thereby forming a white background of barium sulphate in the solution, adding sodium fluoride to the solution in an amount sufficient to react completely with the sodium aluminate, thereby regenerating the alkalinity of said aluminate to twice its original amount, and again titrating to the neutral end point with a 2.56 normal solution of sulfuric acid and measuring the respective amounts of said sulfuric acid solution required in both of the aforesaid titration steps.

PERLE N. BURKARD.
